UNITED STATES PATENT OFFICE

2,369,738

INTERNAL-COMBUSTION ENGINE

Laney N. Johnson, Columbus, Ga.

Application September 22, 1942, Serial No. 459,305

1 Claim. (Cl. 123—78)

My invention relates to improvements in internal combustion engines, the principal object in view being to equip such engines with efficient, simply constructed mechanism of few parts for scavenging the cylinders of all burnt gases on the exhaust up-stroke of the pistons, and which is adapted for incorporation in present-day engines without material changes in the basic structure of such engines.

Other and subordinate objects are also comprehended by my invention, all of which, together with the precise nature of my improvements, will be readily understood when the succeeding description and claim are read with reference to the drawings accompanying and forming part of this specification.

In said drawings:

Figure 1 is a fragmentary view in vertical section illustrating my invention in a preferred embodiment thereof.

Figure 2 is a similar view taken on the line 2—2 of Figure 1.

Figure 3 is a diagrammatic view illustrating the position of the parts in the intermediate intake stroke position of the piston.

Figure 4 is a similar view illustrating the parts in the intermediate compression stroke position of the piston.

Figure 5 is a similar view illustrating the position of the parts in the approximate limit of the compression stroke of the piston.

Figure 6 is another similar view illustrating the position of the parts at the beginning of the power stroke of said piston.

Figure 7 is another similar view with the parts shown in the position they assume in the intermediate power stroke position of the piston.

Figure 8 is another similar view with the parts positioned as in the intermediate exhaust stroke position of said piston.

Figure 9 is another similar view with the parts shown in the position they assume near the limit of the exhaust stroke of said piston, and

Figure 10 is a view in vertical section of a modification of the invention.

Referring now to the drawings by numerals, and first to Figures 1 to 9, wherein my improvements have been illustrated as embodied in a four-cycle engine of the in-line type having poppet valves and an overhead cam shaft such as are used for aircraft engines, 1 designates one of the cylinders surmounting the crank case 2 and surmounted by a head casting 3 having the usual spark plug 4 turned therein. The piston is designated 5, the crank shaft 6 and the connecting

rod 7. The overhead cam shaft 8 journaled in bearings, as at 9', operates the valve rockers 9, 10 for the intake and exhaust poppet valves 11, 12 to open the same in opposition to the springs 13 and through the medium of the cams 13' on said cam shaft, all in the usual and well understood manner.

According to my invention, the head casting 3 embodies an integral, auxiliary cylinder 14, coaxial with the cylinder 1 and forming a diametrically reduced extension thereof opening into the top of the same, the diameter and length of the cylinder 14 depending on the bore of the cylinder 1 and the stroke of the piston 5 for reasons which will presently become apparent.

An auxiliary piston 15 is provided in the cylinder 14. The cam shaft 8 is provided with a crank 16 operatively connected to the auxiliary piston 15 by the usual type of connecting rod 17. For reasons which will be understood, the cam shaft 8 in the type of engine illustrated is driven at half the speed of the crank shaft 6, as, for instance, through the medium of a sprocket and chain drive 8' between said shafts. The crank 16 and rod 17 and also the piston 15 are so proportioned that, as shown in Figures 1 and 2, in the limit of up-stroke movement of the piston 5, the auxiliary piston 15 is flush with the inner end of the cylinder 14 and the two pistons are close together leaving substantially no space in the top of the cylinder 1.

Referring now to the operation, through a single cycle of movement of the piston 5, as soon as the piston 5 begins its intake down-stroke, and 35 the intake valve 11 opens, the auxiliary piston 15 begins to rise in the auxiliary cylinder 14, continues to rise slowly during the intake stroke, as illustrated in Figure 3, and during the compression stroke, as illustrated in Figure 4, until 40 the piston 5 reaches the limit of its compression stroke, as shown in Figure 5. During the compression stroke, when, as will be understood, the intake valve 11 is closed, the auxiliary cylinder 14 provides an auxiliary compression chamber, as 45 will be clear. At the beginning of the power stroke of the piston 5, as shown in Figure 6, and during that stroke, as illustrated in Figure 7, the auxiliary piston 15 descends, also during the exhaust stroke, as shown in Figures 8 and 9, until 50 said pistons are close together in the approximate position shown in Figures 1 and 2 and the auxiliary piston 15 flush with the inner end of the auxiliary cylinder 14. During such descent of the auxiliary piston 15, said piston functions 55 to increase the internal pressure against the

burnt gases in the cylinder 1, and, together with the piston 5, to completely force such gases out of said cylinder by way of the usual exhaust port in the cylinder. By providing the auxiliary pressure chamber described and reducing the capacity thereof during the power stroke, a fuel charge may be utilized of greater volume than in ordinary engines with increased operating efficiency.

In Figure 10 my improvements have been shown as embodied in the reciprocating sleeve valve type engine cylinder 18 having the intake and exhaust ports 19, 20 and with which the corresponding ports 21, 22 of the valve sleeve 18' are adapted to register in the usual well known manner. In this embodiment, 23 designates the piston, 24 the crank shaft and 25 the connecting rod. The auxiliary piston 26 is operative, in this instance, in the valve sleeve 18' in conjunction with the piston 23, through the medium of the cam shaft 27 and connecting rod 28. The pistons 23, 26 operate relatively in the same manner and for the same purpose as in the previously described embodiment of my invention.

The foregoing will, it is believed, suffice to impart a clear understanding of my invention without further explanation.

Manifestly, the invention is susceptible of various modifications without departing from the inventive concept, and right is herein reserved to such modifications as fall within the scope of the appended claim.

What I claim is:

In an internal combustion engine including a cylinder and a drive shaft, a cylinder head, a reciprocating piston in said cylinder, valves in said head, and a valve operating cam shaft, an auxiliary cylinder of smaller diameter than the first-mentioned cylinder embodied in said head and forming an axial extension of said first cylinder opening into the head end thereof flush therewith, an auxiliary piston in said auxiliary cylinder, and means to reciprocate said auxiliary piston at substantially one-half the speed of reciprocation of the first-mentioned piston and comprising a crank on said valve operating shaft operatively connected to the auxiliary piston, and a sprocket and chain drive from the drive shaft to the valve operating shaft for rotating said operating shaft at one-half the angular velocity of the drive shaft.

LANEY N. JOHNSON.
